UNITED STATES PATENT OFFICE.

HENRY LEITNER, OF WESTMINSTER, LONDON, ENGLAND.

SCREW PROPELLER.

Application filed March 25, 1919. Serial No. 285,049.

(GRANTED UNDER THE PROVISIONS OF THE ACT OF MARCH 3, 1921, 41 STAT. L., 1313.)

To all whom it may concern:

Be it known that I, HENRY LEITNER, a subject of the King of Great Britain, residing at 3 Victoria Street, Westminster, London, England, have invented new and useful Improvements in Screw Propellers (for which I have filed applications in Great Britain on March 26, 1915, Patent No. 4743, and on August 24, 1915, No. 12178), of which

10 the following is a specification.

My invention relates to screw propellers chiefly designed for use on air-craft, and to that class of propeller in which the blades are hollow, and are composed of separate

15 sheet metal plates welded or otherwise suitably joined together at the edges.

The object of my invention is to improve the construction of propellers of this type, and to this end I form two or more blades 20 of a propeller together, by rolling, stamping, or otherwise shaping to the required thickness and form a pair of sheet metal plates, each plate forming the front surface of one blade and the rear surface of an adjacent blade. In general it will be advantageous to form the blades in pairs as for a two-bladed propeller, but it is obvious that propellers having more than two blades may

25 be formed in a similar manner.

30 The plates which form a pair of blades are shaped at the centre so as to enclose either wholly or partially a convenient form of hub or boss, as, for example, a tubular or a spool-shaped hub. To the sides of this hub a pair of plates shaped as above described are securely fixed by welding, soldering or other suitable means, and the edges of the said plates are then welded or soldered together all around, and finished off by

35 grinding or otherwise.

40 Such propeller blades may be supported or strengthened internally by any suitable or special means, such, for example, as those described in my Patent No. 1,328,005 dated

45 Jan. 13, 1920.

50 It will be understood that there are two such shaped plates for each pair of blades, one for the front face of one blade and the rear face of the other blade, and one for the rear face of the first blade and the front face of the second blade. After these have been put together, and their edges suitably united, the remainder of the hub portion may be covered or filled in with thin sheet

metal, united at the edges with the existing 55 plates. These filling-in pieces are not, however, in any way required for the purpose of strength.

A propeller thus formed may be fitted to the driving shaft by having suitable holes 60 cut in the centre of the plates of the hub portion, as, for example, hexagon holes, or a circular hole with a key-way, or key-ways.

If required, however, a central tube may be inserted, and welded or otherwise attached to the plates, but this is not essential 65 to my invention which admits of the propeller being mounted in a variety of ways.

In order that my invention may be clearly understood, I will describe it by reference 70 to the accompanying drawings, in which:—

Figure 1 is a view of a two-bladed propeller of an ordinary design or shape, and constructed according to the invention.

Figure 2 is a longitudinal sectional view 75 of the same.

Figure 3 is a section on the line 3—3, Figure 1.

Figure 4 is a perspective view of the two plates used in forming a propeller of ordinary design or shape.

Referring to the drawings which show a two-bladed propeller, the said blades are formed from two sheet-metal plates, one of which plates forms the surface *a* of the two 85 blades, and the other the surface *b* thereof, so that when the shaped plates are placed together two complete blades are formed. It will be seen that each plate forms the front face of one blade and the rear face of the 90 other blade.

c is the hub which is of a tubular or spool-shape and the sides of this hub are enclosed by the two blades *a* and *b* which are secured to it by welding, soldering, or other suitable 95 means.

As above stated, the blades may be strengthened internally by suitable means, such as those described in the patent above referred to and which consists of liners with 100 or without projecting strengthening ribs.

d represents pieces of thin sheet-metal with which the spaces left at the ends of the hub between the plates *a* and *b* constituting the blades, are filled in.

The hub occupies a position in the twist of the blades like a rod passing between the strands of a double strand rope. In a three

or four bladed propeller, the hub will occupy a similar position but it will be understood that each plate in the latter arrangement passes around a less portion of the hub than will be the case with a two bladed propeller.

Having now particularly described and ascertained the nature of my said invention and in what manner the same is to be formed, I declare that what I claim is:—

1. A hollow metal plural bladed propeller

formed of a plurality of plates, each of which is shaped to form the leading side of one blade and the trailing side of another blade.

2. A hollow metal plural bladed propeller formed of a plurality of plates, each of which is shaped to constitute the leading side of one blade and the trailing side of another blade, the abutting edges of said blades being connected together.

HENRY LEITNER.
